ROCK BREAKER

Joseph W. Ady, Jr., and Robert D. Wilfley, Colorado Springs, Colo.

Application June 26, 1933, Serial No. 677,642

7 Claims. (Cl. 83—46)

This invention relates to rock-breakers of the general type of apparatus used in reducing ores and other similar materials to a size suitable for the separation of values by concentration, flotation, amalgamation or other methods.

It is an object of the present invention to provide a machine of the above-stated character, in which simplicity of construction is combined with great efficiency and practicability in use.

A further object is to provide a rock-breaking machine capable of variations in proportions within practical limits, to regulate the intensity of the breaking action according to varying conditions and differing materials, and still other objects reside in details of construction as will be set forth in the course of the following description.

In the accompanying drawings, in the several views of which like parts are similarly designated,

Figure 1 represents a plan view of a machine embodying the distinctive features of the invention,

Figure 2 is a sectional elevation taken on the line 2—2 of Figure 1, and

Figure 3 is a vertical section along the line 3—3 of Figure 1.

The principal elements of the machine are two endless elevating conveyors disposed with relation to each other, so that material delivered from either, will be picked up by the other to be again raised to an elevated point of discharge. The material discharged from the elevators falls through space onto respective breaker-elements by which the ore or other material is reduced, and the two conveyors thus co-operate to reduce the material to the desired fineness.

In the drawings, the two elevators 5 slant in opposite directions to move in intersecting planes.

The elevators are of the bucket-conveyor type, each comprising an endless belt 6 carrying a plurality of buckets 7 in equidistant spaced relation to each other. It is to be understood that endless chains or other carriers may be substituted for the belts.

The endless carriers are mounted upon rotary sheaves, drums or sprocket wheels 8 and 9, the lower ones of which are mounted for rotation in a tank 10, while the upper ones are supported in bearings 12 on a superstructure 13.

Pulleys 14 on the shafts of the upper sheaves or wheels serve for the operation of the two conveyors by connection with a conveniently located motor or other source of energy.

Owing to their slanting position, material dis- charged at the upper ends of the two elevators

will fall through space, and series of spaced breaker bars 15 are disposed in the tank to intercept the falling matter, and by the resulting impact, reduce the rocks and other constituents of the material to greater fineness.

The upper or impact faces of the breaker bars may be rounded as shown in the drawings, so that fine particles of material adhering thereto may be dislodged by the impact of other matter in the continued operation of the machine. Water or other liquid is supplied to the tank through valve-controlled conduits 16 and overflow openings 17 in opposite sides of the tank, establish a liquid-level 18 beneath the breaker elements.

The tank has a central wall 19 for the bearings which support the shafts of the lower sheaves or wheels 8 of the elevators, but the spaces beneath the breaker-elements communicate so that matter passing through the bars of either element may pass to a point below the conveyor associated with the other element, for re-elevation.

The sides of the tank extend inwardly, as at 20, to provide bearings for the opposite ends of the shafts of the lower sheaves or wheels of the conveyors.

In the operation of the machine, material to be reduced is fed into the tank at any convenient point thereof.

The two elevators moving in the direction of the arrows shown in Figure 3 of the drawings, 30 pick the material from the tank and carry it to the elevated points of delivery. The material discharged from the elevators drops through space to fall upon the respective breaker-elements, and the impact of the material with the bars of the 35 latter, reduces the material to greater fineness.

The reduced matter settling in the body of liquid constantly supplied to the tank, builds up, slides and is otherwise compelled to move from either end of the tank to the other, so that the 40 matter discharged from either elevator after having passed through the spaces between the bars of the respective breaker-element, will move to the region of the tank in the path of the buckets of the other elevator to be re-elevated and further 45 reduced by impact with the other breaker-element. Material eventually reduced to the desired fineness floats from the tank through the openings 17 into launders 21 or other conduits.

It will thus be apparent that the machine comprises two units, A and B, each including an elevator and a breaker element, which cooperate to reduce the material by moving the same alternately to elevated points of delivery, and it is a distinctive and important feature of the inven- 55

tion that by lengthening or shortening the conveyors, the elevation of the points of delivery above the breaker elements may be so regulated as to vary the intensity of the impact of the material with the breaker elements to any desired degree within practical limits.

It is to be understood that variations in the construction and arrangement of the elements and parts included in the apparatus as hereinabove described and shown in the drawings, may be resorted to within the scope and spirit of the invention.

What we claim and desire to secure by Letters Patent is:

1. A rock breaker comprising a tank having an overflow determining a liquid level therein, two upwardly ranging conveyors in the tank, each having its intake below the liquid level and having its discharge at a predetermined elevation above said liquid level, the conveyors being inclined to dispose the discharge of one in substantially the same vertical plane as the intake of the other, a breaker disposed in the path of material descending from each discharge by gravity, and a hydraulic inlet acting on settled material in the bottom of the tank for moving the same to a conveyor intake.

2. A rock breaker comprising a tank having an overflow determining a liquid level therein, two upwardly ranging conveyors in the tank, each having its intake below the liquid level and having its discharge at a predetermined elevation above said liquid level, the conveyors being inclined to dispose the discharge of one in substantially the same vertical plane as the intake of the other, and breakers disposed above the liquid level in the path of material descending from each discharge by gravity.

3. A rock breaker comprising a tank having an overflow determining a liquid level therein, two upwardly ranging conveyors in the tank, each having its intake below the liquid level and having its discharge at a predetermined elevation above said liquid level, the conveyors being inclined to dispose the discharge of one in substantially the same vertical plane as the intake of the other, and two rows of spaced breaker-bars disposed in the path of material descending from each discharge by gravity, the bars of one row being in vertical alignment with the spaces in the other row.

4. A rock breaker comprising a tank having an overflow determining a liquid level therein, two

upwardly ranging conveyors in the tank, each having its intake below the liquid level and having its discharge at a predetermined elevation above said liquid level, the conveyors being inclined to dispose the discharge of one in substantially the same vertical plane as the intake of the other, a breaker disposed in the path of material descending from each discharge by gravity, and a hydraulic inlet acting on settled material in the bottom of the tank for moving the same to each conveyor intake.

5. A rock breaker comprising a receptacle for material to be broken, two upwardly-ranging conveyors in the receptacle, each having its intake in the lower portion of the receptacle and having its discharge at a selective elevation above the receptacle, the conveyors being inclined to dispose the discharge of one in substantially the same vertical plane as the intake of the other, and a breaker disposed in the path of material descending from each discharge by gravity, to act on and direct the discharged material to the intake of the other conveyor.

6. A rock breaker comprising a receptacle for material to be broken, two upwardly-ranging conveyors in the receptacle, each having its intake in the lower portion of the receptacle and having its discharge at a selective elevation above the receptacle, the conveyors being inclined to dispose the discharge of one in substantially the same vertical plane as the intake of the other, a breaker disposed in the path of material descending from each discharge by gravity, and means for varying the elevation of the conveyor discharge relative to the breaker.

7. A rock breaker comprising a receptacle for material to be broken, two upwardly-ranging conveyors in the receptacle, each having its intake in the lower portion of the receptacle and having its discharge at a selective elevation above the receptacle, the conveyors being inclined to dispose the discharge of one in substantially the same vertical plane as the intake of the other, and a plurality of spaced breaker-bars disposed in the path of material descending from each discharge by gravity, each of said bars having its upper surface rounded to resist the deposit of material thereon and effective for directing the material after impact to the intake of the other conveyor whereby to provide a circulatory movement of material through the receptacle.
